UNITED STATES PATENT OFFICE.

WILLIAM J. SLOAN, OF PITTSBURGH, PENNSYLVANIA.

GLOBE-HOLDER.

1,010,681.

Specification of Letters Patent. Patented Nov. 29, 1911.

Application filed February 13, 1911. Serial No. 668,237.

To all whom it may concern:

Be it known that I, WILLIAM J. SLOAN, a citizen of the United States of America, residing at Pittsburgh, in the county of Allegheny and State of Pennsylvania, have invented certain new and useful Improvements in Globe-Holders, of which the following is a specification, reference being had therein to the accompanying drawing.

10 This invention relates to a globe holder, particularly designed for gas and electric light fixtures, and the primary object of the invention is to obviate the necessity of using screws for connecting the upper edges of a 15 globe to a holder.

Another object of the invention is to provide a globe holding device that can be advantageously used in connection with inverted mantle gas fixtures, the device allowing for expansion and contraction of the glass globe and thereby preventing any breakage due to the globe being too tightly held in the holder.

Further objects of the invention are to 25 provide a globe holding device that is simple in construction, durable, easy to manipulate and highly efficient for the purposes for which it is intended.

With the above and other objects in view, 30 the invention resides in the novel construction, combination and arrangement of parts to be hereinafter specifically described and then particularly claimed.

In the drawing:—Figure 1 is a perspective view of the globe holding device, Fig. 2 is a horizontal sectional view of the same, and Fig. 3 is a vertical sectional view of a portion of the device.

The reference numeral 1 denotes the goose-neck of a gas fixture, one end of the neck having a needle valve 2 and an air mixer 3, and the opposite end of the neck having a dome 4 provided with an annular flange 5 and upper and lower circumferentially arranged ribs or beads 6 and 7. The flange 5 is provided with three equally spaced and radially disposed openings 8 and movably arranged in these openings are gripping pins 9 having the inner ends thereof provided 45 with heads 10 and the outer ends secured to resilient arms 11, said arms being riveted or otherwise connected, as at 12 to the flange 5.

Slidably mounted upon the flange 5 between the beads 6 and 7 is a band 13 made 50 of a metallic strip having the ends 14 thereof

bent outwardly and soldered, riveted or otherwise connected together to form a handle by which the band is shifted upon the flange 5. The band 13 adjacent to the ends 14 thereof is provided with longitudinal slots 15 and extending through these slots are stops 16, carried by the flange 5 and adapted to limit the shifting movement of the band upon the flange 5, said stops serving functionally as handles, either of which can be gripped in connection with the ends 14 of the band 13 to facilitate the shifting of the band upon the flange 5.

The band 13 is provided with an off-set circumferentially arranged portion 17 providing clearance for the riveted ends of the arms 11, and said band adjacent to said arms is provided with slots 18 which allow the arms 11 and the gripping pins 9 to extend through the band and serve functionally for the purpose for which they are employed.

When the band 13 is shifted in one direction, the arms 11 normally hold the pins 9 out of engagement with the upper flanged edge of a globe 19 thereby allowing the globe 20 to be removed from the dome, but when the band is shifted in the opposite direction, the band engages the arms 11, forcing said arms inwardly, together with the pins 9 and thereby causing the headed ends 10 of said pins to engage the upper edge of the globe 19 and firmly support the same.

From the foregoing it will be observed that I have devised a novel globe holder that can be used in connection with various kinds of light fixtures, and it is obvious that the holder can be made of light and durable metal and finished to conform in appearance to the fixture in connection with which it is used.

What I claim is:—

A globe holder comprising an annular member adapted to be supported from the lamp support, a plurality of resilient fingers secured at one end to and externally of said member in spaced apart relation, each finger having an inwardly-extending gripping pin, said member having an opening for and through which each pin extends, an annular operating ring external of and supported by said member, said ring and member having their directions of width in parallel planes, said ring being offset circumferentially to form an annular recess within which said fingers extend, said offset having elong-

gated openings through which the free end of the fingers are adapted to extend, said ring being formed with a projecting operating handle and being additionally slotted 5 on opposite sides of and adjacent said handle, and stop pins carried by said member and projecting through said slots, said member forming a shield inside of the fingers to

prevent direct heat contact with the fingers from the burner.

In testimony whereof I affix my signature in the presence of two witnesses.

WILLIAM J. SLOAN.
